THOMAS S. HOMANS, OF HEMPSTEAD, NEW YORK, ASSIGNOR TO INTERTYPE CORPORATION, OF NEW YORK, N. Y., A CORPORATION OF NEW YORK.

SLUG-TRIMMING KNIFE FOR LINE-CASTING MACHINES.

1,202,720.

Specification of Letters Patent. Patented Oct. 24, 1916.

Application filed April 11, 1916. Serial No. 90,484.

To all whom it may concern:

Be it known that I, THOMAS S. HOMANS, a citizen of the United States, residing at Hempstead, in the county of Nassau and State of New York, have invented new and useful Improvements in Slug-Trimming Knives for Line-Casting Machines, of which the following is a specification.

My present invention relates to improvements in line casting machines, and more especially to those of the linotype class wherein type slugs are cast from lines of matrices, the slugs being ejected from the mold and forced between a pair of knives which trim the flat sides of the slugs to the proper thicknesses according to the different sizes of type.

In linotype machines as heretofore constructed, the slug trimming means embodied a pair of knives, one of which was movable or adjustable and was usually mounted to slide transversely of its length, but owing to the limited space available in the machine, the guiding means for the movable or adjustable knife could not be made sufficiently long in proportion to the length of the knife to insure accurate parallelism between the knives. In order to trim slugs of various thicknesses according to the different sizes of type required, it is desirable that this adjustment between the knives be made with great accuracy in order that the slugs may be trimmed with their flat sides in absolute parallelism and to exact size.

The object of the present invention is to provide improved means for guiding, adjusting and holding the movable or adjustable slug trimming knife at the proper distance from the co-operating knife to insure precision in the trimming of the slugs whereby the slugs will be trimmed accurately according to the size of the type and the opposite sides of the slug will be in precise parallelism, the knife-adjusting means being of a character that will enable the necessary adjustments to be made quickly and with ease.

To these and other ends, the invention consists in certain improvements, and combinations and arrangements of parts, all as will be hereinafter described, the novel features being pointed out particularly in the claims at the end of the specification.

In the accompanying drawing: Figure 1 represents an axial or longitudinal section

through a slug trimming device constructed in accordance with the present invention. Fig. 2 is an end view of the same, looking toward the left in Fig. 1. Fig. 3 is a perspective view of the movable or adjustable knife and its adjusting means. Fig. 4 is a detail perspective view of the dial for setting the knife. Fig. 5 is a detail view of one end of the adjustable knife and the co-operating parts showing means for adjusting the movable knife on its carrying head or slide.

Similar parts are designated by the same reference characters in the several views.

The present invention is applicable generally to typographical machines of the type adapted to cast type slugs from lines of matrices. The invention is shown and will be hereinafter described as applied to a slug trimming device of a type adapted for use especially on line casting machines of the linotype class. It is to be understood, however, that the invention is not restricted to the particular construction and arrangement shown, as equivalent constructions and arrangements are contemplated and will be included within the scope of the claims.

In the present instance, 1 designates a portion of the vise frame of a machine of the linotype class, the same having one of the slug trimming knives 2 fixed thereon, and 3 designates the knife block which is fixed to the vise frame. The adjustable or movable slug trimming knife 4 is mounted on a head or slide 5, the latter being slideable on the knife block. As shown, a pair of screws 6 serve to secure the knife 4 upon the slide 5. If desired, the under side of the slide 5 may be provided with a T-slot 7 to receive a T-shaped key 8 secured to the knife block. This slot and key may, however, be dispensed with, if desired. The knife 4 is properly set relatively to the slide 5 by a set-screw 9 which is carried at each end of the slide 5 and bears against the adjacent edge of the knife 4. Preferably, a screw 10 is tapped into each end of the knife 4 and extends through an opening in the slide 5, a compression spring 11 operating between the slide 5 and the head of the screw 10 and serving to hold the knife 4 in engagement with the set-screws 9. The slide 5 is secured to a second slide 12 by screws or equivalent means 13, the second slide having a spindle 14 thereon, and this

spindle is formed with a chamber 15 to contain a coiled compression spring 16, one end of the spring bearing against the closed end of the spindle 14, while the opposite end of the spring bears against an arm 17 which is secured by the screw 18 to the knife block. The spring 16 operates on the spindle 14 to retract the adjustable or movable knife 4 relatively to the fixed knife 2, it acting through the medium of the slides 5 and 12. An adjusting screw 19 is provided, it having a relatively long hub which is accurately fitted to rotate on the spindle 14. The periphery of the adjusting screw is formed with accurately cut threads 20 which cooperate with a correspondingly threaded portion 21 which is fixed to or forms a part of the knife block 3. A hand-wheel 22 is provided for adjusting the screw 19 to set the knives for the trimming of slugs of different thicknesses. As shown, this hand-wheel is fixed to the adjusting screw by a suitable number of screws 23 which extend through segmental slots 24 in the hand-wheel and are tapped into the face of the adjusting screw. The periphery of the hand-wheel is provided with a scale 25 which is graduated in accordance with the different thicknesses of type slugs, and an index or pointer 26 is attached at a suitable point to the knife block and it enables the hand-wheel to be set so as to space the trimming knives at the proper distance according to the size of the type slug to be trimmed.

In the operation of machines of the linotype class, each slug cast in the mold from a line of matrices is ejected therefrom by an ejector, and this ejector pushes the slug between the trimming knives. The trimming knives are set by manipulation of the hand-wheel so as to provide a space between them corresponding to the thickness of the type slug to be produced. The knives must be set in precise parallelism and maintained in parallelism during the trimming of the slugs in order that the flat sides of the slugs will be precisely parallel. It is also desirable to set and maintain the knives at precisely the correct spacing in order to trim the slugs to the exact thickness corresponding to the size of type to be produced. Upon reference to Fig. 2 it will be observed that the knife 4 has a sloping or inclined edge which causes a deviation of this edge of the knife from a right angle to the line of movement of the slug as the latter passes between the knives. This deviation from the right angle is desirable, as it produces a shearing cut, but it produces a thrust first upon the higher end of the knife or the end of the knife which is first engaged by the slug, and this thrust has a tendency to twist the knife. The present invention provides means for effectively sustaining this twist-

ing tendency and for maintaining the knives in precise parallelism. As shown, the slide 12 which carries the knife 4 is provided toward its extreme ends with pads 27 which are adapted to bear against or coöperate with an accurately finished and true surface 28 formed on the adjacent face of the adjusting screw 19, the adjusting screw being of a relatively large diameter and preferably of a diameter as nearly equal to the length of the knife as is practicable. Owing to this relatively large diameter of the adjusting screw and its engagement with the threaded portion 21 of the knife block, the adjusting screw has a relatively firm and true support, which will prevent deflection thereof when subjected to pressure in an axial direction at one point toward or at its periphery. With this arrangement, when the thrust first comes upon the higher end of the knife 4 or the end thereof which is first engaged by the slug, the pad 27 opposite to that end of the knife will bear against the adjusting screw at or near the periphery thereof, and as the adjusting screw is firmly supported at its periphery by the rigid portion 21 of the knife block, twisting or deflection of the knife 4 is prevented. The pad 27 at the opposite end of the knife sustains the thrust imposed thereon, and the thrust of this pad in turn is sustained by the adjusting screw at or near the periphery thereof, accurate setting and precise parallelism of the knives being thereby maintained.

To vary the setting of the knives for the trimming of slugs of different thicknesses according to the varying sizes of type, it is only necessary to rotate the hand-wheel 22 in the appropriate direction until the index or pointer 26 registers with the appropriate graduation on the dial 25. Compensation for wear or grinding of the knives is provided for by the screws 23 and the segmental slots 24. Should such compensation become necessary, the hand-wheel can be reset relatively to the adjusting screw in order that the index or pointer 26 will read correctly with the dial 25. Compensation for uneven wear or grinding of the knives is provided for by the set-screws 9. Lost motion between the different parts, and particularly between the thread of the adjusting screw and the support 21, is taken up automatically by the spring 16 which exerts an end thrust on the screw but allows the latter to move axially to effect the different adjustments or settings of the knives. This spring also holds the pads 27 firmly against the co-operating surface formed on the face of the adjusting screw.

I claim:

1. Slug trimming means for line casting machines comprising coöoperative knives relatively adjustable to trim slugs of differ-

- ent thicknesses, and means for relatively adjusting said knives embodying an adjusting screw of a diameter approximately as great as the length of the working edges of the 5 knives, means coöperating with the threaded portion of the screw to sustain axial thrust thereon, and abutments between one of the knives and the peripheral portion of the screw for sustaining thrust at any point on 10 the cutting edge of such knife.
2. In a line casting machine, the combination of a support, a knife mounted to move on the support transversely of its length, a screw threaded into the support for adjusting 15 the knife to the required settings, the diameter of the screw being approximately equal to the length of the working edge of the knife, and abutting surfaces between the 20 knife and the rim of the screw to resist the pressure at any point of the cutting edge of the knife.
3. Slug trimming means for line casting machines comprising a support, a relatively fixed knife thereon, a coöperating adjustable 25 knife capable of being set at different distances from the fixed knife, an adjusting screw for said knife having its thread coöperating with said support and provided with a thrust-sustaining surface of a diameter 30 approximately equal to the length of the cutting edge of the adjustable knife, and thrust-sustaining abutments interposed between the thrust-sustaining surface of the screw and the ends of the adjustable knife.
- 35 4. Slug trimming means for line casting machines comprising a support, a relatively fixed knife thereon, a coöperating adjustable knife capable of being set at different distances from the fixed knife, a slide carrying 40 the adjustable knife and provided with thrust-sustaining abutments located behind the respective end portions of such knife, and an adjusting screw having its thread

coöperating with said support and provided with a peripheral thrust-sustaining surface 45 to coöperate with said thrust-sustaining abutments.

5. Slug trimming means for line casting machines comprising a support, a relatively fixed knife thereon, a coöperating adjustable 50 knife capable of being set at different distances from the fixed knife, a slide carrying the adjustable knife and provided with thrust-sustaining abutments located behind the respective end portions of such knife, 55 the slide having a spindle thereon, and an adjusting screw mounted rotatably on said spindle and having its thread coöperative with said support, the screw having a thrust-sustaining surface near its rim coöperative 60 with said thrust-sustaining abutments.

6. In a line casting machine, a fixed and movable knife, a spring centrally disposed urging the movable knife in one direction, and a screw to adjust the knife in the reverse direction, said screw abutting the knife 65 at opposite ends to secure parallel movement of the knife against the spring.

7. Slug trimming means for line casting machines comprising a support, coöoperative 70 relatively adjustable knives, a member carrying one of the knives and having thrust-sustaining pads thereon, an adjusting screw having its thread coöperative with the support and having a thrust-sustaining face 75 coöperative with said thrust-sustaining pads, and a spring acting to hold said pads against said face and to produce an axial thrust between the screw and said support.

In testimony whereof I have hereunto set 80 my hand in presence of two subscribing witnesses.

THOMAS S. HOMANS.
